GAPS TO MAINTAIN BALANCED PRESSURE
CONTACT

George Hantscho, Tuckahoe, N.Y., assignor to George Hantscho Company, Inc., a corporation of New York
Filed Aug. 22, 1962, Ser. No. 218,587
1 Claim. (Cl. 101—220)

The present invention relates to improvements in offset printing apparatus.

In the offset printing processes as carried out in multi-stage web presses, the equipment for each printing stage or station includes a pair of inked plate cylinders, each carrying matter to be printed on the two sides of the paper web, and offset or blanket cylinders for transferring the ink images from the plate cylinders to the paper in the desired registry. The transfer surfaces on the offset cylinders are provided by sheets or blankets wrapped about the cylinders and secured thereto by suitable clamping means disposed in transverse slots extending throughout the lengths of the rollers. During the actual printing operation, the two blanket cylinders also serve as backing or impression cylinders each for the other, the moving web engaging both in a common narrow transverse contact zone so that both sides of the paper are printed at the same time. The two blanket cylinders are phased so that the blanket joints of both revolve through the common zone and in registry with the spacing or transverse border area between successive printings or signatures.

It is recognized that for best results in multiple impression work, and particularly multi-color printing, precise registry of successive overlying images is required, calling in turn for extreme accuracy in spacing and timing between and throughout the apparatus and prevention of slip between the paper and the printing rollers. One difficulty that has been encountered concerns the gaps in the blanket surfaces created by the means for fastening the blankets to the blanket cylinders. These gaps, which are necessarily of significant width and which as hitherto practiced are phased to pass through the printing zone in simultaneous axial registry with each other, cause a momentary release of the gripping pressure between the cylinders and permit some slip to occur. To alleviate this tendency, means have been proposed to create friction between the web and the blanket rolls outside the printing zone, for example, by tilting the tangential plane of the printing zone out of registry with the normal plane of the paper web advancing through the machine, thereby causing frictional wraps of the web about the blanket cylinders before and after passage between the latter. However, in addition to repeated undesirable distortions of the inked or partially inked web from the accurate ideal of straight tangential progress throughout the various units of the press assembly, such supplementary measures in general rely for frictional grip on a small component of the tension of the web itself, which does not alter the fact that the accurate and powerful pressure grip of the blanket cylinders is still interrupted by passage of the straight transversely aligned blanket gaps irrespective of the tangential plane of the print zone.

One object of the present invention resides in the provision of an improved offset printing apparatus adapted to maintain uninterrupted compressional gripping pressure on a receiving web passing between a pair of co-operative blanket cylinders throughout continuous passage of the web between the cylinders.

Another object resides in the provision of an improved offset printing apparatus adapted to exert uninterrupted gripping pressure on a web moving between a pair of

2

cooperative transfer or blanket cylinders throughout continuous movement of the web in a flat plane tangent to the peripheries of the cylinders.

A further object is to provide an improved offset printing transfer cylinder structure including a basic cylinder and a circumferential blanket secured thereto with a narrow securing joint extending across the blanket at a predetermined angle with the axis of the basic cylinder.

A further object is to provide improved offset printing apparatus including a pair of tangentially disposed blanketed transfer cylinders having narrow blanket securing joints extending transversely in circumferentially skewed relation to the axes of their respective cylinders, the cylinders being so rotarily timed as to cause the two blanket joints to pass through the zone of tangency at substantially the same time.

A further object resides in the provision of printing rollers in which the directions of skew of the roller gaps or slots are such as to permit the two gaps to pass through the tangential zone in substantially crisscross relation.

A further object resides in the provision of printing rollers in which the directions of skew of the roller gaps or slots are such as to permit the two gaps to pass through the tangential zone in substantial correspondence throughout.

A further object is to provide improved offset printing apparatus for continuous web printing including a plurality of successive printing units each having a pair of cooperative transfer cylinders adapted mutually to maintain uninterrupted gripping pressure on the web during the entire passage of the web between them, whereby slip between the web and the units is prevented throughout the printing succession.

In the drawings:

FIGURE 1 is a vertical sectional view of a typical pair of blanketed transfer cylinders as applied in a preferred form of the invention.

FIGURE 2 is a diagrammatic illustration of a multiple unit press embodying the invention.

FIGURE 3 is a simplified perspective view of a transfer cylinder illustrating the skewing of the blanket joint.

FIGURE 4a is a front elevation of a pair of cooperative offset or transfer cylinders illustrating the blanket joints as arranged for intersecting or crisscross operation.

FIGURE 4b is a plan view of the web showing in dot-and-dash development the paths of the blanket joints across the web when the latter is passed between cylinders with joints skewed as in FIGURE 4a.

FIGURE 5a is a view similar to FIGURE 4a but illustrating the blanket joints as arranged for correspondence as they pass through the tangential zone.

FIGURE 5b is a plan view of the web showing the combined paths of the blanket joints with the skew arrangement of FIGURE 6, and

FIGURE 6 is a view of a blanket cylinder illustrating the actual smallness of the skew angle required by the invention in typical practice.

With respect to the above drawings, it will be understood that to afford clarity of illustration, such factors as blanket gap widths and angles of skew have in most part been exaggerated in order to show properly their relationship within the invention. FIG. 6 serves to illustrate the fact that in practice these factors may involve relative dimensions too small to exhibit the relationships clearly when drawn to the necessary small scale.

Referring to FIG. 1, the numerals 20 and 21 generally denote parallel upper and lower rotary offset or transfer cylinders adapted to compressional engage a paper web 22 in a common narrow zone of tangency T and to transfer ink images to the top and bottom faces of the web respectively from upper and lower plate or type

cylinders 24 and 25 in the usual offset printing manner. The upper transfer cylinder structure 20 includes a basic cylinder 26 upon which is wound a peripheral blanket 27 which provides the actual transfer surface, the lower cylinder structure 21 similarly including a basic cylinder 28 carrying a blanket 29. The ends of the blankets 27 and 29 are secured in transverse slots or recesses 30 and 31 in their respective basic cylinders. The clamping of the blanket ends within the slots may be accomplished by any suitable means such as the structure illustrated, which being per se well known in the art need only be briefly described as typically applied to blanket 27.

The respective opposite ends of the blanket are clamped between pairs of narrow bars at 32 and 33. One of the sets of clamping bars 32 is retained in a suitable groove 34 in the wall of the recess 30, while the second set 33 is held in a rotatably adjustable cylindrical clamping member 35 journalled in a transverse block 36, the block being secured in the basic cylinder by screws 37 and forming in effect an integral portion thereof upon assembly. In set-up, turning the member 36 clockwise causes the latter to stretch the blanket 27 and hold it in firm peripheral engagement with the basic cylinder 26. In such position the clamping member is locked at the ends of the cylinder by means which, as previously noted, are well known in the art and accordingly require no detail description herein. Similarly, as the construction and operation of the clamping means for the lower blanket 29 is the same as that described for the upper structure except for rotational direction, further detail description of the lower structure is omitted as unduly repetitious. It will be noted, however, that the necessary clearance between the end portions of the upper blanket 27 on emergence from the clamping recess 30 creates a narrow gap 39 in the true peripheral surface of the blanketed cylinder, this gap extending throughout the width of the blanket. A similar gap 40 exists in the case of the lower blanket 29. It has been the presence of such gaps extending across the blanket surfaces in parallel with the cylinder axes as in the prior art, which has caused the interruption of compressive gripping pressure on the web and consequent slippage as previously noted. The manner in which the present invention eliminates this difficulty is as follows:

Referring to FIG. 3, which depicts the upper blanket cylinder 20, it will be seen that the gap 39, instead of extending across the blanket in parallel with the cylinder axis A, is circumferentially skewed so that one edge of the gap subtends a peripheral arc B of uninterrupted peripheral surface at the rear side of the blanket 27, this subtended surface tapering in a triangular area C to the front side of the blanket. Similarly, the other edge of the gap subtends a second surface triangle C₁ tapering to the rear side of the blanket.

The peripheral extent of each arc B (defined of course by the width of blanket and the angle of skew) is such that throughout the combined peripheral extent of the two arcs B, no narrow zone T can extend across the blanket parallel to the cylinder axis A without encountering one or both of the triangular areas C and C₁. In other words, the zone T at all times includes a portion of uninterrupted peripheral blanket surface, so that the triangular areas may appropriately be termed continuity triangles.

Referring to FIG. 4a, which shows the front or in-feed aspect, the gaps 39 and 40 appear canted in the same direction, though operationally they are skewed in opposite directions due to the opposite rotation of their respective cylinders, so that as they pass conjunctively through the print zone T, they encounter the web 22 in the crisscross pattern illustrated in phantom in FIG. 4b. Since both the upper and lower skewed gaps subtend pairs of continuity triangles as explained in connection with FIG. 3, various peripheral areas of the two blanket

cylinders always remain in mutual compressive relation with the web 22. Thus in the central position illustrated in FIG. 4b, the mutual pressure areas extend inwardly for equal distances D from the edges of the web. As the web continues to move through the zone T, the compressive pressure shifts from the outer areas to the central portion of the crisscross pattern, the shift occurring in overlapping relation so that no release can occur. It will be obvious that a similar overlapping shift has occurred in reverse order during the entry of the gap combination to the zone T. Thus, it will be seen that the invention provides a plurality of operationally overlapping gripping pressure areas spanning the entire passage of the gaps 39 and 40 through the zone T, maintaining continuity of compressive grip on the web 22 at all times and thereby preventing any possible slip. The apparatus is so phased that the passage of the blanket joints takes place in registry with the desired blank zone 23 on the web being printed.

In the alternative arrangement shown in FIG. 5a, the joint gaps 39 and 40 are skewed in the same operational direction so as to pass through the zone T in correspondence, generating the single sloping pattern 39a-40a illustrated in FIG. 5b. The operation of this embodiment is the same as that described above except that the overlapping shift of compressive pressure application along the zone T takes place from a single decreasing area E extending inward from one edge of the web 22 to a similar but increasing area E₁ extending inward from the opposite edge. Obviously this arrangement effectively maintains the continuity of compressive gripping pressure with consequent prevention of slip in the manner set forth.

As previously noted, the angles of skew have been necessarily illustrated in exaggerated aspect for purposes of clarity in explaining their essential part in the invention. In practice these angles, which for any given installation are functions of the blanket breadth, gap width and width of the contact or printing zone T, are quite small, as illustrated by angle Q in FIG. 6. The width of T, which is the narrow flattened tangential area in which the blanket cylinders engage the web 22, is of course, dependent on the cylinder diameters, the applied pressure, and the thickness and compressibility of the blankets. In the arrangement illustrated in FIGS. 5a and 5b, which affords minimum angle requirement, the governing relation is that the skew advance or arc B (FIG. 3), shall be significantly greater than the gap width minus the width of the zone T. Thus, for example, with T width of $\frac{1}{4}$ inch and net gap width of $\frac{5}{16}$ inch, an arc B or skew advance of $\frac{3}{16}$ inch affords sufficient gripping lap for satisfactory operation as described. In such case, assuming a typical blanket breadth of 36 inches, the skew angle Q may be in the order of .3 degree, while for a 48-inch blanket, the skew angle may be significantly smaller.

The extreme smallness of the required skew angles is an advantage in manufacture, allowing the clamping means to be mounted directly across the basic cylinders while confining the skewing to the lips of the clamping recesses, though obviously the illustrated clamping means or their equivalent may also be incorporated in skewed position, if desired. The skewed gaps may similarly be formed either helically or as straight lines, the smallness of the peripheral angles making the two virtually identical.

From the foregoing description throughout, it will be evident that by the introduction of the skewed clamping gaps in the operational combination set forth, the invention achieves with maximum simplicity a new and highly useful improvement in the offset printing art, i.e., the maintenance of uninterrupted gripping pressure on a moving web by the blanketed transfer cylinders themselves within the contact or print zone, eliminating requirement for any other anti-slip provision and rendering the combination particularly well adapted to such advantageous straight tangential multi-unit installations as that diagram-

matically illustrated in FIG. 2, though obviously not limited thereto. It is also evident that the apparatus is readily adaptable to a variety of press sizes and services, and that various skew angles and gap combinations may be employed while retaining the feature of operationally overlapping grip pressure surfaces. The utilization of skewed gaps is generally advantageous in other related applications in printing presses to insure relatively constant gripping pressure between cooperating rollers to prevent relative slip and avoid bouncing which often occurs as the result of the momentary release of pressure between cooperating rollers.

Thus, while the invention has been set forth in preferred form, it is not limited to the exact embodiments illustrated, as various modifications may be made without departing from the inventive concept within the scope of the appended claim.

What is claimed is:

In an offset web printing press, in combination, a blanket transfer cylinder including blanket-securing means establishing a transverse gap joint in the peripheral blanket surface of said cylinder, a second blanket transfer cylinder disposed in tangential parallelism with said first cylinder and establishing mutually therewith a contact zone of compressive gripping pressure on a web passing be- 25

20 tween said cylinders, and blanket-securing means establishing a transverse gap joint disposed in the peripheral blanket surface of said second cylinder and orientated to move through said contact zone conjunctively with said 5 first gap joint, said transverse gap joints being peripherally skewed with respect to the axes of their respective cylinders at predetermined operationally opposite directional angles, said skewed gap joints move through said contact zone in crisscross relationship producing mutual pressure areas extending inwardly from opposite sides of the web and which areas increase as the central contact area 10 decreases until the gaps are in centered crisscross relationship in the contact zone whereupon said central contact area increases as the side pressure areas decrease thereby 15 effecting a balanced gripping pressure on said web as the gaps move through the contact zone.
